UNITED STATES PATENT OFFICE.

EDWARD LEVIN, OF BROOKLYN, NEW YORK.

SECTIONAL GARMENT-FORM.

1,160,420.

Specification of Letters Patent. Patented Nov. 16, 1915.

Application filed November 18, 1914. Serial No. 872,692.

To all whom it may concern:

Be it known that I, EDWARD LEVIN, a subject of the Czar of Russia, residing at Brooklyn, Kings county, State of New York, have invented certain new and useful Improvements in Sectional Garment-Forms, of which the following is a full, clear, and exact description.

This invention relates to an improvement in garment-forms, but more particularly to that class of garment-forms consisting of a plurality of adjustably connected sections.

One of the objects of this invention is to provide a sectional garment-form with adjustable connections arranged for convenient manipulation exteriorly of the form so that it will not be necessary to place the hands within the form when it is necessary to adjust the sections relatively to each other.

To carry out the object of the invention, I provide each section with a cut out portion, alining one with the other, whereby a substantially rectangular or other shaped opening is provided within which I locate a handwheel by means of which the adjusting devices can be manipulated.

Other features of improvement will hereinafter appear.

To the foregoing and other ends my invention is directed and I will now proceed to describe and finally claim the novel features thereof, reference being had to the accompanying drawings, forming part hereof, wherein—

Figure 1 is a front view of a garment-form embodying my invention; Fig. 2 is a side view of the form, the standard being omitted; Fig. 3 is a sectional plan view, the section being taken on a line 3—3 in Fig. 1; Fig. 4 is an enlarged sectional detail view, partly in elevation, of the upper end of the standard, a portion of the form being also shown, the section being taken on a line 4—4 in Fig. 5; Fig. 5 is a sectional plan view thereof, the section being taken on a line 5—5 in Fig. 4, and Fig. 6 is an enlarged fragmentary sectional view, the section being taken on a line 6—6 in Fig. 1.

As herein embodied, a garment-form to which my invention is applied is indicated by A, the same consisting of a plurality of bust-sections 1, 2, 3 and 4, and a plurality of hip-sections 5, 6, 7 and 8. In this instance, the form is split vertically at the front, sides and back, and horizontally at the waist line.

The form, as a whole, is carried by a standard B, consisting of a tubular member 9, which in turn carries, at its upper end, a rotatable threaded spindle 10, by which means the bust and hip portions are separated to alter the length of the waist.

To adjustably support the bust-portion at the neck region, I provide each bust section 1, 2, 3 and 4 with an adjusting plate 11 slidably engaging a guideway 12 in a plate 13, rotatably mounted on the spindle 10. In other words, the spindle 10 passes loosely through the plate 13. The plate 13 rests upon a collar 14 carried by the spindle 10. The spindle 10 also carries a threaded sleeve 14^a which carries an operating-wheel 15 for the thrust-plate 16, between which and the plates 11 is located a pad 17 of leather, rubber or the like. The sleeve 14^a is secured to the spindle 10 by a pin 18. To rotate the spindle 10, I provide the same with a hand-wheel 19.

To cause the spindle 10 to move longitudinally of the tubular member 9 to adjust the length of the waist, I provide the upper end of the standard member 9 with a threaded head or nut 20, which is engaged by the threads on the spindle 10.

For the purpose of adjusting the bust and hip-sections toward or away from each other, I provide each of said sections with a pivotally secured bracket 21. The brackets 21 are arranged in sets, one on each section and in alinement, one bracket in each set being provided with a right-hand thread, the other with a left-hand thread.

To coöperate with the brackets 21, I provide each set with a spindle 22 having right and left threads to engage the threads in the brackets 21. Each spindle 22 is provided with a handwheel 23, by which means the spindle is rotated. When the spindles 22 are rotated, the sections of the form will be adjusted either toward or away from each other according to the direction of rotation of the handwheel.

During the adjustment of the bust-sections, the plates 11 will correspondingly slide in the guideways 12, and when the bust-sections have been adjusted the lock-wheel will be manipulated to force the pad 17 against the plates 11, thereby locking them in position. When the hip sections are adjusted, they will swing upon the links 110 24 which connect them to the plate 25 on the standard member 9.

As can be seen in Figs. 1 and 2, each form section is provided with aligned cut out portions 26 to form an opening in which the hand wheels 23 are located.

5 To manipulate the handwheels, it is not necessary to place the hands within the form, this being apparent. With my improved adjustable connections, I am enabled to obtain a degree of adjustment of 10 great nicety in a convenient and speedy manner by manipulation of the handwheels 23.

It should be noted that although the brackets 21 are pivotally secured to the form-sections, the connection is none the 15 less made sufficiently rigid to prevent wobbling of the brackets; and that by reason of this pivotal connection, the form-sections may be opened up angularly or in V-like positions; if the brackets 21 were rigidly 20 connected to the form-sections, such angular adjustments would be impracticable.

Having now described my invention, what I claim and desire to secure by Letters Patent, is:

25 1. In combination with an adjustable sectional garment-form, a standard therefor, a plate carried by each bust section, means carried by the standard slidably engaging said plates, means to lock said plates against 30 movement, brackets pivotally secured to contiguous sections, spindles connecting said brackets on contiguous sections provided with right and left hand threads, and means operable exteriorly of the form to rotate 35 said spindles.

2. In combination with the sections of an adjustable sectional garment-form, a pivotally secured bracket carried by each section located in alignment one with the other, 40 one of said brackets being provided with a

right hand thread, the other with a left hand thread, a spindle provided with right and left hand threads engaging said brackets, and a handwheel carried by the spindle.

3. In a sectional garment-form, contiguous sections being provided with aligned cut-out portions to form an opening, a threaded spindle extending across said opening, a handwheel carried by the spindle and located adjacent said opening, and means pivotally secured to the sections engaging the threads on said spindle. 45 50

4. In combination with the sections of an adjustable garment-form, brackets pivotally secured to contiguous sections, the brackets being in substantial alignment, a spindle connecting said brackets, and means to operate the spindle whereby to cause the brackets and connected sections to be drawn toward or away from each other. 55 60

5. In combination with an adjustable sectional garment-form, bust-sections having neck-portions, a standard therefor, a spindle, a plate rotatably mounted on said spindle and provided with guideways, adjusting plates connected to the neck portions of said bust-sections and slidably engaging said guideways, a thrust-plate carried by said spindle, a threaded sleeve secured to the spindle, said sleeve being provided with an operating-wheel, a pad located between the thrust-plate and said adjusting plates, and a hand-wheel to rotate the spindle. 65 70

Signed at New York city, N. Y., this 14 day of November, 1914.

EDWARD LEVIN.
